CIRCULATOR PUMP STRUCTURE

William R. Ray, Los Angeles, Calif., assignor to
General Controls Co., a corporation of Calif-
ornia

Application September 3, 1946, Serial No. 694,474

2 Claims. (Cl. 103—87)

1

This invention relates to a centrifugal pump structure, and more particularly to a circulating pump for hot water.

It is an object of this invention to provide an improved structure of this character.

It is another object of this invention to provide a unitary structure, including a pump and an electric motor for driving the pump, which is particularly adapted for handling hot water.

As is well understood, it is necessary to provide means about the pump shaft, where it extends from the pump chamber, to prevent leakage of water along the shaft, such means commonly comprising a single seal between the interior and exterior of the pump chamber. It is another object of this invention to provide an improved seal for this purpose.

It is another object of this invention to provide a seal structure incorporating means for lubricating the sealing surfaces.

It is another object of this invention to provide a seal structure incorporating a double seal, one for the shaft leaving the pump chamber, the other for the shaft entering the driving motor housing. It is still another object of this invention to provide a seal structure having an improved mode of assembly and disassembly.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claims.

In the drawing:

Figure 1 is a longitudinal axial section through a structure incorporating the features of the invention;

Fig. 2 is a cross-section partly in elevation taken as indicated by line 2—2 on Fig. 1; and

Fig. 3 is a detail section of the seal structure.

Referring to Fig. 1 of the drawing, the circulator comprises a unitary structure 1 including a centrifugal pump 2 directly connected to an electric motor 3, the pump impeller 4 being arranged to be supported by the motor bearings (not shown). Thus, the motor shaft 5 is shown as having an extension 6 threaded on a reduced portion of the shaft 5-a, the impeller 4 being secured on extension 6 as by one or more set screws 4-a.

2

The body 7 forms the pump chamber 8 and has an inlet nozzle 9 and an outlet nozzle 10, each of which is exteriorly threaded, as at 11, for receiving a conventional union coupling (not shown). The body 7 is connected to the system piping by the aid of these couplings, the entire unit 1 being supported thereby.

The body 7 has openings 12 and 13 through its opposite sides, the opening 12 being closed by 10 a detachable pressed metal cover 14. The opposite opening 13 is closed by a member 16, conveniently formed as a casting and providing an intermediate chamber 17 through which the shaft 5 extends.

The member 16 serves to mount the motor 3 15 on the pump body 7 and, additionally, has a cylindrical flange 18 to which is secured, as by a soldering or brazing process, a sheet metal housing 19 which forms a chamber enclosing the motor 3. This chamber is filled with an appropriate insulating and lubricating liquid through 20 an opening 20 (see Fig. 2) provided with a conventional filler cup 21 having a spring lid 22. The housing 19 is provided with cooling fins 23 for preventing excessive temperature rise of the 25 motor 3, which is subjected to the heat of the hot water handled by the pump 2, as well as to its normal heat of operation.

The motor 3 is supported in the housing 19 by 30 means of a threaded stud 24 on the motor frame projecting through a suitable opening in the back wall 19-a of the housing 19 and engaged by a nut 25. Leakage of oil is prevented by a suitable sealing washer 26. The opposite end of the 35 motor is supported by a boss 27 on the motor frame seated in a suitable recess 28 in the casting 16.

The housing 19 has an opening 29 in its upper portion through which the motor leads 30 and 31 extend into a closed space 32, defined by a 40 member 33 suitably secured on the housing 19. The member 33 has an intermediate wall 34 through which a pair of glass seals 35 and 36 extend, carrying extensions 30-a and 31-a respectively of the leads 30 and 31. These extensions 30-a and 31-a may be connected to a power source in a conventional manner through the 45 threaded opening 37. The filler opening 21 may be formed conveniently in the member 33.

To prevent leakage from the pump chamber 8 50 along the shaft 5, a seal structure 40 is provided in the intermediate chamber 17. Since it is desired to lubricate the sealing surfaces, and to isolate the lubricant from the motor chamber 20, the structure 40 comprises a double seal.

Referring to Fig. 3, a collar 41 having opposite

3

annular faces 42 and 43 is mounted on shaft 5, as by being suitably secured to the inner end of the shaft extension 6, centrally of chamber 17. One end of chamber 17 is closed by the wall 17-a formed integrally with the casting 16. The opposite end is closed by a cap 44 threaded into the member 16. The wall 17-a and the cap 44 respectively have clearance apertures 45 and 46 for the shaft 5.

A non-rotary seal member 47 is adapted to cooperate with one surface of the collar 41, and for this purpose has a reduced annular surface 47-a for contacting the collar surface 42. The opposite surface of member 47 has a circular recess 47-b for accommodating, in a fluid-tight manner, a ring or washer 50 secured to one end of a Sylphon or metallic bellows 51. The other end of bellows 51 has a similar ring 52 secured thereon, which seats in a fluid-tight manner in a recess 17-b formed in the chamber end wall 17-a. The Sylphon 51 has considerable resilience, creating a seating force between the rings 50 and 52 and their respective recesses, as well as urging member 47 to seal against the collar 41. However, to ensure sufficient force for this purpose, a compression spring 54 may be confined between the rings 50 and 52, urging them apart. It will be understood from the described construction that the member 47, when contacting the member 41, is in fluid-tight relation with the wall 17-a, isolating the lubricant chamber 17 from the motor chamber.

A similar arrangement serves to isolate the pump chamber 8 from the chamber 17. Thus, a non-rotary seal member 55 engages the face 43 of the collar 41, and has a recess for accommodating the end ring 56 of a Sylphon 57. The opposite end ring 58 is accommodated in a recess 44-a in the cap 44. A compression spring 59 may be provided between rings 56 and 58 for urging the rings to seat in their recesses in a fluid-tight manner, as well as for urging the member 55 to seal against the collar 41.

It is desirable to lubricate the sealing surfaces between the collar 41 and the members 47 and 55. For this purpose the chamber 17 is arranged to contain a suitable lubricant. An upwardly extending passage 60, opening through the upper part of the casting 16, is provided for filling the chamber. This passage may be closed by a spring capped filler cup 61. A similar downwardly extending passage 62, closed as by a pet cock 63, serves to drain the chamber 17 when desired.

The described construction of the seal 40 renders its assembly and disassembly for inspection and repair a simple matter. Thus, with the pump 2 and motor 3 assembled as in Figs. 1 and 3, the seal structure 40 may be disassembled as follows. The cover 14 is first removed from the pump body 7. The impeller 4 is then removed from the shaft extension 6, the set screw 4-a having been loosened for this purpose. The cap 44 is then unscrewed from the member 16 and removed by axial movement to the right along the shaft 5. The Sylphon structure 56-57-58 and the sealing member 55 are then removed by a similar movement to the right.

After this, the shaft extension 6 is disconnected from the shaft 5 by appropriate rotation with respect to the shaft to unscrew the threaded connection 5-a, and the extension 6, together with the collar 41, is removed. This frees the seal member 47, as well as the Sylphon 50-51-52, and allows them to be removed from 75

4

chamber 17 by movement to the right along the shaft 5. It will be noted that this does not require disconnection of the pump body 7 and the motor 2, or any disturbance of the pump connections.

In assembling the seal, the Sylphon 50-51-52 is first inserted in the chamber 17, with either end ring 50 or 52 seated in the recess 17-b. The seal member 47 is then mounted on the outer end ring 52 or 50 as the case may be, and the shaft extension 6, with collar 41, secured on shaft 5. The other seal member 55, together with the Sylphon 56-57-58, are inserted in the chamber 17, which is then closed by the cap 44. The impeller 4 is then secured on the extension 6, and the cover 14 secured on the pump body 7.

The inventor claims:

1. In a centrifugal pump structure: a casing having a partition dividing said casing into an inlet chamber and an outlet chamber; said casing having aligned conduit means forming an inlet and an outlet passageway cooperating with said inlet and outlet chambers respectively; said partition having an opening; said casing having a pair of aligned apertures opening exteriorly of said casing from the inlet chamber and outlet chamber respectively; said pair of apertures being aligned with said opening; a bracket secured to said casing and cooperating with the aperture of said casing on the inlet side, and defining an auxiliary chamber; a motor supported on that side of said bracket remote from said casing, said motor having a shaft extending through said opening into said outlet chamber; a seal structure between said shaft and said bracket for preventing flow of fluid between said auxiliary chamber and said inlet chamber; means detachably securing said seal structure to said bracket; said seal structure being of such size as to permit passage thereof through said opening and said aligned apertures; a runner in the outlet chamber cooperating with the opening and detachably secured to said shaft, said runner being of such size as to permit passage thereof through the aperture of said casing on the outlet side; and a cover plate for the aperture of said casing on said outlet side.

2. In a centrifugal pump structure: a casing having a partition dividing said casing into an inlet chamber and an outlet chamber; said casing having aligned conduit means forming an inlet and an outlet passageway cooperating with said inlet and outlet chambers respectively; said partition having an opening; said casing having a pair of aligned apertures opening exteriorly of said casing from the inlet chamber and outlet chamber respectively; said pair of apertures being aligned with said opening; a bracket secured to said casing and cooperating with the aperture of said casing on the inlet side, and defining an auxiliary chamber; a motor supported on that side of said bracket remote from said casing, said motor having a shaft; a shaft extension detachably connected to said shaft, said extension extending through said opening and into said outlet chamber; a collar carried by said extension; a first seal structure cooperating with said collar for preventing flow of fluid from the exterior of said bracket along said shaft into said auxiliary chamber, said first seal structure being of such size as to permit passage thereof through said pair of apertures and said opening upon detachment of said extension; a second seal structure cooperating with said collar for preventing flow of fluid from said inlet chamber along said shaft into said

auxiliary chamber; means for detachably securing said second seal structure to said bracket; said detachably securing means, said second seal structure, said extension, and said collar being of such size as to permit passage thereof through 5 said pair of apertures and said opening; a runner detachably secured to said extension, and mounted in said outlet chamber, said runner co-operating with said opening, said runner being of such size as to permit passage thereof through 10 the aperture of said casing on the outlet side; and a cover plate for the aperture of said casing on said outlet side.
